UNITED STATES PATENT OFFICE

110,266

DESIGN FOR A FLATIRON

Leo Ivan Bruce, Jr., Framingham, Mass., assignor
to The Fitzgerald Manufacturing Company,
Winsted, Conn., a corporation of Connecticut

Application March 14, 1938, Serial No. 75,805

Term of patent 14 years

To all whom it may concern:

Be it known that I, Leo Ivan Bruce, Jr., a citizen of the United States, residing at Framingham, in the county of Middlesex and Commonwealth of Massachusetts, have invented a new, original, and ornamental Design for a Flatiron, of which the following is a specification, reference being had to the accompanying drawings forming a part thereof.

Figure 1 is a side elevational view of a flatiron showing my new design,

Figure 2 is a top plan view thereof, and

Figure 3 is an end view of one half of the flatiron shown in Figure 1.

I claim:

The ornamental design for a flatiron, as shown.

LEO IVAN BRUCE, JR.
